(57) **CLAIM**

The ornamental design for a rounded platform toy brick as shown and described.

DESCRIPTION

FIG. 1 is a top perspective view of a rounded platform toy brick.

FIG. 2 is a bottom perspective view of the rounded platform toy brick.

FIG. 3 is a second, top perspective view of the rounded platform toy brick.

FIG. 4 is a second, bottom perspective view of the rounded platform toy brick.

FIG. 5 is a front plan view of the rounded platform toy brick.

FIG. 6 is a back plan view of the rounded platform toy brick.

FIG. 7 is a side plan view of the rounded platform toy brick.

FIG. 8 is a second, side plan view of the rounded platform toy brick.

FIG. 9 is a top plan view of the rounded platform toy brick.

FIG. 10 is a bottom plan view of the rounded platform toy brick.

FIG. 11 is a top perspective view of a second embodiment of the rounded platform toy brick.

FIG. 12 is a bottom perspective view of the second embodiment of the rounded platform toy brick.

FIG. 13 is a second, top perspective view of the second embodiment of the rounded platform toy brick.

FIG. 14 is a second, bottom perspective view of the second embodiment of the rounded platform toy brick.

FIG. 15 is a front plan view of the second embodiment of the rounded platform toy brick.

FIG. 16 is a back plan view of the second embodiment of the rounded platform toy brick.

FIG. 17 is a side plan view of the second embodiment of the rounded platform toy brick.

FIG. 18 is a second, side plan view of the second embodiment of the rounded platform toy brick.

FIG. 19 is a top plan view of the second embodiment of the rounded platform toy brick; and,

FIG. 20 is a bottom plan view of the second embodiment of the rounded platform toy brick.

The broken lines in the figures show features of the rounded platform toy brick that form no part of the claimed design.
